(57) **CLAIM**

The ornamental design for a vehicle, as shown and described.

DESCRIPTION

FIG. 1 is a front, right side perspective view of the vehicle of the present invention with the top down;

FIG. 2 is a rear, right side perspective view thereof;

FIG. 3 is a rear elevational view thereof;

FIG. 4 is a right side view thereof, the left side view being a mirror image of FIG. 4;

FIG. 5 is a front elevational view thereof;

FIG. 6 is a right side view as in FIG. 4, with the top up;

FIG. 7 is a front, right side perspective view as in FIG. 1, with the top up;

FIG. 8 is a rear, right side perspective view as in FIG. 2, with the top up;

FIG. 9 is a front elevational view as in FIG. 5, with the top up; and,

FIG. 10 is a rear elevational view as in FIG. 3 with the top up.
